UNITED STATES PATENT OFFICE.

EMERY LIBERTY, OF NEW YORK, N. Y., ASSIGNOR OF ONE-HALF TO DAVID NEVIUS, OF NEW YORK, N. Y.

TELLER'S WINDOW.

No. 848,756.

Specification of Letters Patent.

Patented April 2, 1907.

Application filed March 21, 1906. Serial No. 307,178.

To all whom it may concern:

Be it known that I, EMERY LIBERTY, a citizen of the United States, residing in the borough of Manhattan, city of New York, county and State of New York, have invented certain new and useful Improvements in Tellers' Windows, of which the following is a specification.

This invention relates to improvements in tellers' windows of the type shown in my Patent No. 774,190, dated November 8, 1904, which is characterized by a window which may be elevated above the counter, so that a larger opening will be produced when desired.

The objects of the present invention are to simplify the construction of the mechanism, render it more certain and silent in operation, and other objects, which will more fully appear from the following specification and claims.

I attain these objects by the mechanism illustrated in the accompanying drawings, in which—

Figure 1 is a perspective view of a window, counter, and operating mechanism for the wicket. Fig. 2 is a top view of the operating mechanism, and Fig. 3 a side elevation thereof. Fig. 4 is a detail of the portion of the mechanism shown in Fig. 3, showing the parts in the position they will assume with the wicket raised.

In all the views like parts are designated by the same reference characters.

In carrying out my invention I provide the wicket or window 1, which is arranged above the counter 2, as disclosed in my patent before referred to. The wicket 1 has depending side portions 3, which pass through openings in the counter and slide within the guides or ways 4 in the sides of the window. Provision is made to permit the wicket to be raised to the position shown by the dotted lines in Fig. 1. This raising mechanism is as follows: The two depending portions 3 are connected together by the horizontal cross-piece 5. To this cross-piece is secured a vertical lifting-rod 6. The upper end of the latter may be forked, as shown, and secured to the cross-piece 5 by means of a pin, so that an exact nicety of alinement between the rod 6 and depending portions 3 is not necessary to be attained in order to get a smooth operation. The rod 6 extends down below the counter and passes through a guide or bracket, which is shown as an angular plate

with a hole through it, through which the rod 6 passes. This guide or bracket 7 is secured to a backing 8, which may be a plate of sheet metal, a board, or other device, secured to a portion of the support of the counter. The 60 elevating mechanism and lock are secured to and carried by the backing 8.

The elevating mechanism comprises a chain 9, which is secured to the rod 6 by means of a clip 10. This chain 9 passes over 65 a sprocket-wheel 11, which is mounted upon a shaft 12, which turns in bearings carried by the backing 8, and a frame 13, formed of an upright piece and a horizontal piece connected together, as shown. The other end of 70 the chain 9 is connected to a counterweight 14. This counterweight is in the form of a box, having a bail to which the chain is attached and provided with the clips 15, which engage with a guide-rail. The guide-rail 16 75 is vertically arranged in a proper position so that the weight 14 will slide up and down upon it. The guide-rail is T-shaped in cross-section (see Fig. 2) and is secured by bolts or rivets to the backing 8, the shape of the 80 rail permitting the clips 15 to engage with the edges of the rail and to guide the counterweight, preventing it from coming out of contact with the rail. The box constituting the counterweight may be made with walls 85 sufficiently thick to constitute a sufficient weight, or if additional weight is required it can be made by introducing shot or other weights into the box 14.

The sprocket 11 is rotated by means of a 90 pinion 17, free to turn upon the shaft 12 (see Fig. 2) and provided with a finger 18. This finger is adapted to engage with the finger 18^a, carried by the sprocket 11, when the pinion 17 is rotated, and thereby constitutes a 95 lost-motion connection between the pinion and sprocket. The pinion 17 is rotated by means of a rack 19, which is connected to and carried by a rod 20. The rod 20 passes through a hole in the bracket 7, and its lower 100 extremity is connected to a pedal 21. As shown in Fig. 1, the pedal 21 is fulcrumed upon a support 22, which rests upon the floor, and its inner end is connected to the lower end of the rod 20 by means of a link 23, a 105 second link 24, formed of a plate engaging between notches in the extremities of the link 23 and rod 20, connecting the two latter together. The rod 20, rack 19, and lever 21 are so arranged that upon the teller depress-

ing the outer end of the pedal with his foot the rod and rack 19 will be elevated, rotating the pinion 17 and causing the finger 18 to engage with the finger 18^a, which in turn will 5 rotate the sprocket 11, lift the rod 6, and with it the wicket 1. The sprocket 11 is preferably made sufficiently large so that the wicket may be completely elevated through not more than one revolution of the sprocket. 10 The rack 19 is held in engagement with the pinion 17 by means of a roller 25, which is carried upon a support 26, which is secured to the backing or base plate 8 by means of screws, which pass through slots in the support 15 and permit of adjustment of movement of the roller 25 in relation to the rack 19.

In order to prevent the wicket from being elevated except by the pedal, a lock is provided. This lock, as shown, consists of a 20 friction-clutch, which engages with the rod 6. The clutch is shown as formed of a plate 27, which has a central opening through which passes the rod 6. This plate is secured by a screw 28 to the bracket 7. The opening 25 through which the rod 6 passes is sufficiently large to make a loose fit, and the connection with the plate 27 and screw 28 is sufficiently loose to permit some movement of the plate upon the bracket. This plate will serve 30 the purpose of a clutch to prevent the elevation of the rod 6 except by the pedal. It is pressed upward into engagement with the rod by means of a spiral spring 29, which surrounds the rod and also engages with the plate 27. The other extremity engages with a second bracket 30, through which the rod 6 also passes. As shown in the drawings, the brackets 7 and 30 are formed of one piece of sheet metal bent to the shape illustrated to 35 40 form a support for the clutch-plate 27 and the end of the spring 29.

The plate 27 is depressed by means of a dog 31, which is carried in bearings on a standard 32, which in turn is supported by 45 the bracket 7. One end of the dog engages with the clutch 27. The other end comes in contact with a cam-plate 33, carried by the rod 20, by means of which it may be tilted. This cam-plate 33 extends up above the 50 bracket 7 only a short distance and ends at a point below the dog 31 when the plate 33 and rod 20 are in the lowermost position. This lowermost position is determined by a stop 34, which may be in the form of a pin passing through the rod and engaging with the bracket 7. It will be seen that when the parts are in position shown in Fig. 3 the dog 31 will merely rest on the top of the cam-plate 33, allowing the spring at 29 to elevate 55 60 the clutch-plate 27 and cause the latter to lock the rod 6 against vertical movement. When the rod 20 is elevated, the dog 31 will be engaged by the top of the cam-plate 33 and tilted, depressing the clutch-plate 27 and 65 permitting the rod 6 to be elevated.

The operation of the device is as follows: Ordinarily checks, pass-books, &c., are passed over the counter 2 and under the wicket 1. Should it be necessary for any purpose to increase the size of the window-opening, the teller depresses the pedal 21. This elevates the rod 20 and rack 19, rotating the pinion 17. It also elevates the cam 33, depresses the clutch 27 through the agency of the dog 31, and will permit the elevation 70 of the rod 6 and with it the wicket 1. The pinion 17 is free to rotate a certain distance before the fingers 18 and 18^a come into engagement. This distance is sufficient to permit the elevation of the cam 33 a sufficient distance to cause a disengagement of the clutch 27 with the rod 6. As soon as this has occurred the fingers 18 and 18^a will come into contact with each other and the sprocket 11 will be rotated by the rotary 85 movement of the pinion 17. This will elevate the chain 9 and rod 6 and with it the wicket 1. The wicket will remain open so long as pressure is applied to the pedal 21. Upon the teller removing pressure from the 90 pedal the weight of the rack 19, rod 20, and cam 33 will be sufficient to quickly overbalance the other side of the pedal. The parts will immediately descend to the position shown in Fig. 3. This will not rotate 95 the sprocket 11, for the reason that the pinion 17 will be free to rotate in the other direction for nearly a complete revolution before the fingers 18 and 18^a will again come in contact. Pressure having been removed from 100 the pedal 21 and the rod 20, cam 33, and rack 19 having been allowed to descend, the wicket will descend also, but not so rapidly, as it is counterbalanced to some extent by the counterweight 14. The clutch 27, however, will be put into action the moment the cam 33 has entirely descended. Consequently 105 the wicket will be locked against further open movement. Should an attempt be made to open the wicket after the pressure has been 110 removed from the pedal 21, such attempt will be unsuccessful, because the wicket will be guarded against open movement by means of the clutch 27. The clutch 27 will act noiselessly and yet will be effective at any 115 point of the vertical movement of the rod 6.

In order to prevent a too sudden jar upon the closing of the wicket, the lower end of the rod 9 may be provided with a rubber button 35, which is adapted to engage with a 120 bracket 36, carried by the support 8.

By mounting the lifting and locking mechanism upon the support 8 the parts may be adjusted before being put in place. It is not absolutely essential that the rod 6 engage with 125 the center of the cross-bar 5, although the nearer it is to the center the less liability there will be of jamming in elevating the wicket.

By the construction described a single ele- 130

vating device is employed. This has the advantage over my previous patent, which employs a duplex arrangement engaging with each side of the wicket. I find in practice that this is not necessary, and a single chain, clutch, &c., may be employed with equal success.

Having now described my invention, what I claim as new, and desire to secure by Letters Patent, is—

1. In a teller's window, the combination with the wicket, of means for raising the wicket, such means including a rod, and a lock for the wicket, such lock including a friction-clutch engaging with the rod.

2. In a teller's window, the combination with a wicket, of lifting and locking means for the wicket, the said lifting and locking means being carried *in toto* upon a backing-plate, in such a manner as to form an entirety adjustable independently of the wicket, and connections between the lifting and locking means and the wicket.

3. In a teller's window, the combination with the wicket, of a rod for lifting the wicket, a chain and sprocket for lifting the rod, a pinion and a rack for rotating the pinion, and means for moving the rack, a cam moved by the rack, lost-motion connections between the pinion and sprocket, a friction-clutch adapted to engage with the rod, and a dog adapted to engage with the cam and release the clutch.

4. In a teller's window, the combination with a wicket, of means for moving the wicket and means for locking the wicket, such means including a rack, means for moving the rack, a rod, means actuated by the rack for moving the rod, and a friction-clutch engaging with the rod, and a dog actuated by the movement of the rack for disengaging the clutch, and connections between the rod and wicket.

5. In a teller's window, the combination of a backing-plate, a bracket thereon, the said bracket having a guide for the wicket-moving rod, and a plate-clutch for the rod secured to the bracket.

6. In a teller's window, the combination of a backing-plate, a bracket thereon, the said bracket having a guide for the wicket-moving rod, and a plate-clutch secured to the bracket, and a dog carried by the bracket and engaging with the clutch.

7. In a teller's window, the combination of the lifting-rod, and a guide therefor, the said guide being in the form of a bracket, a plate connected to the bracket, and having an opening through which the rod passes, and a spring surrounding the rod and engaging with the plate.

8. In a teller's window, the combination of the wicket and opening mechanism, such mechanism including a chain, and sprocket, and pinion, a rack engaging with the pinion, and a roller engaging with the rack, the said roller being adjustably mounted.

9. In a teller's window, the combination therewith of the opening mechanism including a chain and actuating mechanism therefor, and a counterweight, the said counterweight comprising a box and clips thereon, in engagement with a track of T-section.

10. In a teller's window, the combination of a wicket and a rod for elevating the wicket, means for elevating the rod, and a rubber cushion on the lower end of the rod, and a fixed abutment against which the button will contact when the wicket is closed.

This specification signed and witnessed this 2d day of March, 1906.
